(21) Appl. No.: **29/285,046**

(57) **CLAIM**

(22) Filed: **Mar. 20, 2007**

The ornamental design for an air conditioner/compressor adapter plate, as shown and described.

(51) **LOC (8) Cl. 15-02**

DESCRIPTION

(52) **U.S. Cl. D15/7**

FIG. 1 is a top perspective view of an air conditioner/compressor adapter plate showing my new design;

(58) **Field of Classification Search** D15/7-9;

FIG. 2 is a front view in elevation thereof;

D23/232, 231; 417/359, 415-416, 410.1,
417/321, 265, 405

FIG. 3 is a rear view in elevation thereof;

See application file for complete search history.

FIG. 4 is a side view in elevation thereof;

(56) **References Cited**

FIG. 5 is a side view opposite to that shown in FIG. 4 in elevation thereof;

U.S. PATENT DOCUMENTS

FIG. 6 is a top plan view thereof; and,

D238,963 S * 2/1976 Vinci D15/9

FIG. 7 is a bottom view thereof.
